UNITED STATES PATENT OFFICE.

SIDNEY GEORGE ROWLES, OF ORPINGTON, ENGLAND, ASSIGNOR OF ONE-HALF TO
PERCY ROBERT FENDER, OF LONDON, ENGLAND.

OFFSET PRINTING PRESS.

Application filed July 11, 1923. Serial No. 650,918.

To all whom it may concern:

Be it known that I, SIDNEY GEORGE ROWLES, a subject of the King of Great Britain and Ireland, and a resident of Orpington, county of Kent, England, have invented a certain new and useful Improvement in Offset Printing Presses, of which the following is a specification.

This invention relates to rotary off-set printing presses constructed to print simultaneously on both sides of a web, sheet, or the like in one or more colours.

In machines to effect the foregoing, two contacting resiliently surfaced rollers are so disposed as to receive a web of paper therebetween, each being the complementary impression cylinder of the other, and each being an off-set cylinder. Such off-set cylinders each receive superimposed multi-colour imprints from separately inked printing rolls having metal, stone, or similar surfaces. Other proposals for multi-colour printing from one off-set cylinder embody the use of a plurality of stereotypes, lithographic stones or the like separately inked and imprinting on the off-set cylinder, sometimes with the intervention of a second off-set cylinder in a double off-set press.

The common practice of off-set printing i. e. by conveying planographic imprints to the off-set cylinders, presents no great difficulty as regards "making ready" or packing up but in adapting relief, stereo, letterpress and like work for off-set, the exceptional difficulties experienced generally preclude a practical success. The rotary off-set press, according to the present invention, adopts as one essential, the use of rubber or other resilient or flexible stereos preferably contacting directly with the off-set cylinder; these, owing to their flexibility, can easily be made ready on the stereo rollers, and the yielding contact between stereos and off-set cylinder renders the multi-colour overprinting on the off-set cylinder for stereo work practical and successful. Further, the off-set cylinders are comparatively unaffected by stereo pressure, and consequently good stereo-work and similar results are obtainable when two off-set cylinders co-act for simultaneous back and front printing as previously described.

The said invention therefore consists of an off-set cylinder co-acting with a second off-set cylinder, and more than one stereo

roller carrying resilient stereos forming impressions on each off-set cylinder, each stereo roller being independently inked, the two off-set cylinders each being the complementary impression cylinder of the other. Further, as will be seen from the following description and claims, novel adjustment means for various of the rollers is provided.

In order that the said invention may be readily understood, reference is directed to the following description and accompanying drawing which shows in side elevation a printing machine capable of carrying out the invention.

Referring to the drawings, there is illustrated a construction of plant which lends itself very conveniently to embodiment with a bag-making machine to be driven in conjunction therewith, the whole operating as a single unit for making paper or like bags from a continuous web, and printing on one or both sides of the made-up bag, in any requisite number of colours. The base framework 1 may be either separate, as shown (such, for instance, when the machine is constructed as an independent plant for general off-set printing), or, such framework 1 may be a continuation of the frame of a bag-making or other machine working in unison as aforesaid. In the bed 2, the whole upper structure 3, which carries the various rollers, inking devices, adjustments, and so forth, is slidably mounted so as to be capable of transverse travel across the bed to bring it into alignment with the web, sheets, or articles, being fed between the printing rollers. This transverse adjustment may be effected in any suitable manner, and the numeral 4 indicates the actuating hand-wheel relating thereto. Mounted across the upper structure 3 are the two off-set cylinders 5 and 6 which each becomes the complementary impression cylinder of the other when printing on both sides is taking place. Alternatively, the top of the sheet only can be printed, in which case 5 is merely an impression cylinder and 6 the off-set, or the bottom only can be printed, when 5 becomes the off-set and 6 the impression cylinder.

In the construction shown, cylinder 5 is made the fixed driving cylinder; the end spindles take a bearing through the side slots 7 of the frame 3, and when once positioned and adjusted, it remains perma-

nently. Power is communicated through the chain wheel or pulley 8 indicated by dot-and-dash line, or by other means. The roller 6 is mounted adjustably above said fixed roller 5, and takes a bearing in a block 9 slidably arranged in the slot 10. The block 9 is normally spring-pressed upwardly by the side springs 11, but is held down, keeping the roller 6 under desired contact pressure, in the manner as hereinafter described. An upper block 12, also slidable in the slot 10, carries an adjustment shaft 13, which is supported by resting on the saddle 14 cut in the head of a pin 15. The latter, by its lower extremity, rests in a recess in the upper face of the block 9. The block 12 can be forced down by the screw 16, which lowers the shaft 13 and pin 15, and consequently forces down the roller 6 against spring action. After the main adjustment through the screw 16, a fine or running adjustment to separate the rollers 5 and 6 can be effected in the following way. For a short portion of its length the shaft 13 is formed with a slight cam periphery at the point where it is seated on the saddle 14. Thus, by partially rotating the shaft the eccentric or cam part can be brought on to the saddle and, block 12 being held against upward movement by the screw 16, the pin 15 completes the final downward movement of roller 6, similarly the two rollers 5 and 6 can be separated by a partial rotation of shaft 13, without recourse to the adjustment screw 16. A handle 17 is employed to carry out the foregoing adjustment. It is to be understood that the blocks 9 and 12, the pin 15, spring 11, the eccentric part of the shaft 13, and screw 16, are duplicated on the far side of the machine, with or without a second handle 17. Associated with the off-set rollers 5 and 6 are pairs of stereo rollers 18, 18, and 19, 19 respectively, the spindles of which are dropped into slots in the frame 3 as shown. Each spindle runs in eccentric flanged bearings which are adjustable in such a manner that rotation of the flanges or plates 20 on their own centres (determined by the travel of the arcuate slots 21 over the studs 22) gives a slight movement of the spindles in their slots. By this means the stereo rollers 18, 18, 19, 19, may be adjusted in relation to the off-set rollers 5 and 6. In order to move the top roller 6 away from the co-acting roller 5, there is provided a device whereby the stereo rollers 19, 19 may simultaneously and automatically be moved to obviate jamming of the said off-set roller 6. When the handle 17 is moved to bring the cam of shaft 13 uppermost clear of the saddle 14 and thus cause the rise of the pin 15, block 9 and roller 5 under the action of the spring 11, the eccentric plates 20 of the rollers, 19, 19 are also partly rotated.

The means employed consists of a rocking plate 23 fixed on the shaft 13 and moving with the handle 17. This plate 23 carries a pair of pivoted links 24 which each extends to its respective plate 20 where it is fixed to a stud projecting from the plate 20. Such links 24 are capable of extension and shortening by means of oppositely threaded screw components or otherwise, thus enabling the contact pressure of either stereo cylinder 19, 19 with the off-set roller 6 to be adjusted independently. By means of the handle 17 the top assembly of rollers 19, 19 and 6 can be moved as one complete unit with relation to the roller 5. The four elements, indicated as a whole by the reference numeral 25, represent any convenient and suitable inking gear, the rollers of which supply the stereos mounted on the stereo rollers 19, 19, and 18, 18.

It will be observed that either one, two, three or four stereo rollers can be put into operation in an apparatus constructed according to the foregoing embodiment with the result that top and bottom of the sheet or the like single or together can be printed in one or two colours.

In operation, assuming both sides to be printed in two colours, the rubber or like stereo is fixed to the rollers 19, 19 and 18, 18, and so adjusted that one roller 19 overprints the second colour on to the off-set roller 6 which has received one imprinting from the other roller 19. Similarly, the stereos on the rollers 18, 18, are adjusted to register exactly on the roller 5, and the combined top printings from the off-set roller 6 on to the paper or the like are caused to register with or print in any definite relation to the bottom printings from the lower off-set roller. Although roller 5 is a printing roller, it serves as the impression roller for 6, and vice versa. Cylinder 5 is the master or driver, and all the other rollers and inking apparatus are geared by pinions interior and exterior of the frame 3 as indicated by the interengaging dot-and-dash circles shown.

I claim:—

1. In an off-set printing machine, a framework, an off-set cylinder mounted in a fixed location in said frame-work, a second off-set cylinder mounted above the first off-set cylinder, and means for adjusting said last named off-set cylinder comprising yieldingly mounted journal blocks, saddle-headed pins adapted to engage said blocks, a shaft having an eccentric portion adapted to bear against the saddle-headed pins, and a handle carried by the shaft for rotating the same whereby the pin is forced down or allowed to rise.

2. In an off-set printing machine, a framework, an off-set cylinder mounted in a fixed

- location in said frame-work, a second off-set cylinder mounted above the first off-set cylinder, and means for adjusting said last named off-set cylinder, a pair of stereo rollers mounted below the fixed off-set cylinder, and a pair of stereo rollers adjustably mounted above the upper offset cylinder, and common means for simultaneously adjusting said upper off-set cylinder and said upper stereo rollers.
3. In an off-set printing machine, a framework, an off-set cylinder mounted in a fixed location in said framework, a second off-set cylinder mounted above the first off-set cylinder, and means for adjusting said last named off-set cylinder, a pair of stereo rollers mounted below the fixed off-set cylinder, and a pair of stereo rollers adjustably mounted above the upper offset cylinder, and common means for simultaneously adjusting said upper off-set cylinder and said upper stereo rollers, said means comprising a shaft having an eccentric portion and a pin engaging with the adjustable mounting for the upper off-set roller, eccentric flanged bushings having the upper stereo rollers mounted therein and also having slots in the flanges thereof, studs on the framework of the machine and working in said slots, a rocking plate mounted on the shaft and having an operating handle, and links connecting said rocking plate with the flanged
- bushings for mounting the upper set of stereo rollers.
4. An off-set printing machine, comprising a framework, an off-set cylinder permanently adjusted in said framework, a second off-set cylinder adjustable relatively to the first, each being the complementary impression cylinder of the other, a plurality of stereo rollers to each of the off-set cylinders, said stereo rollers being slidably mounted in the framework to be capable of adjustment relatively to their off-set cylinders and an inking apparatus for each stereo roller, the adjustment means for the adjustable off-set cylinder consisting in journaling its spindles each in a block slidably disposed in a slot in the framework, said block being normally pressed upwards by a spring, an adjustment shaft disposed over the cylinder and parallel thereto, the shaft being rotatably carried in a second pair of blocks also slidable in the slots above the first-mentioned blocks, a pin with a saddle head to support the second blocks upon the first blocks, and a pair of threaded studs extending through the frame to press down or release both pairs of blocks, substantially as herein described.
- In testimony whereof I have affixed my signature hereto this 29th day of June, 1923.

SIDNEY GEORGE ROWLES.
